CLAIM

The ornamental design for an impactor tip as shown and described.

DESCRIPTION

FIG. 1: Is a perspective view of the impactor tip showing the new, original and ornamental design;

FIG. 2: is a top view thereof;

FIG. 3: is a first side view thereof;

FIG. 4: is a second side view thereof; and,

FIG. 5: is a bottom view thereof.

The broken lines in the drawings represent unclaimed portions of the impactor tip and form no part of the claimed design.
